UNITED STATES PATENT OFFICE

WILLIAM FRIEDMAN, OF NEW YORK, N. Y., ASSIGNOR TO LUPÉ, INC., OF NEW YORK,
N. Y., A CORPORATION OF NEW YORK

POWDER SIFTER

Application filed June 24, 1929. Serial No. 373,201.

This invention relates to powder sifters and more particularly to such sifters as are utilized in the dispensing of face powder as required.

The objects of the invention are to provide an improved sifter which will give a constant supply of powder as required until the container is entirely empty; to enable obtaining powder from the container as easily when there is little powder therein as if the container were full of powder; to provide a unitary device for elevating the powder to a relatively stationary dispensing surface; to enable the container to be readily refilled; to secure simplicity of construction and operation; and to obtain other advantages and results as may be brought out in the following description.

Referring to the accompanying drawings in which like numerals of reference indicate similar parts throughout the several views,

Figure 1 is a plan of a powder sifter in open position embodying my invention;

Figures 2 and 3 are sectional views on line 2—2 of Fig. 1 showing the container in open and closed position respectively;

Figures 4 and 5 are views similar to Figs. 2 and 3 but showing a modified construction of the invention; and

Figures 6, 7 and 8 are similar sectional views showing a further modified construction of the invention.

In the specific embodiment of the invention illustrated in said drawings, I have shown a container having hinged members which I will arbitrarily designate as body portion 1 and cover 2. As shown in the drawing, I may provide a metal mirror 3 in the cover hinged at one edge as at 4 so as to provide a closure for said cover when the same is open, and mounting rouge 5 or other make-up material under said mirror so as to be accessible by swinging the mirror open, as will be understood by all persons skilled in this art.

The body portion is constructed for the dispensing of powdered material, such as face powder, and it is in this portion of the container that my invention inheres more particularly. The body portion 1 is provided with a sifting closure 6 hinged thereto at 7

and adapted to close into the upper side of the body portion 1 for completing the same and retaining powder within the body portion. This closure 6 is preferably constructed with a plurality of restricted openings 8 in its surface through which powder may sift. On the top of the main portion of the closure having said openings is a sliding member 9 having corresponding openings 10 which can be brought into registration with said openings 8. The construction is such that the sliding member 9 may be moved to a position where the openings 10 and the openings 8 are not in registration and the powder thereby prevented from sifting through. Preferably the sliding member 9 is arranged to move back and forth with considerable ease so that the user can operate the same back and forth by pressing a powder puff against it and moving the powder puff back and forth. During such operation the powder is forced through the openings as they register and is thereby applied to the powder puff.

In order to apply pressure to the powder so that it will force its way through the openings in the body portion closure when the said openings register, I provide an improved pressure applying and powder supporting means. As shown in Figures 2 and 3 of the drawing I provide a unitary pressure means of spring metal substantially the width of the case so that its edges are in sliding contact with the side walls of the body portion. The upper member 11 of this unitary pressure device has its free end toward the hinged end of the body portion closure and extends to the opposite end of the body portion, turning back again and extending along the bottom wall, as at 12, of the body portion to the hinged end thereof again, turning up transverse to the bottom wall, at 13, toward the said hinge. The parts are so formed and related that the upper member 11 normally tends to swing out of the case by inherent resiliency of the parts and the upstanding end 13 under the hinge has a tendency to swing inwardly toward the other end of the device so that when the top member 11 is forced downwardly it will be engaged at its end by the said upstanding portion 13. Preferably

said upstanding portion 13 is corrugated or otherwise roughened so as to obtain positive contact between the same and the end of member 11 so as to lock said member 11 in place when the two parts become engaged, as indicated in dotted lines in Figure 2.

In the use of the container as described, the pressure member 11 is forced downwardly into the container and is held by one of the 10 corrugations of the upstanding locking member 13 as shown in dotted lines in Figure 2. In that position the user can then pour in a quantity of powder and then close down the closure 6. It is observed that said closure is 15 of a depending or pan shape so that it is closed, the hinge end 14 of the said closure constituting a shoulder which will swing into lateral engagement with said locking member 13 and force it backwardly out of locking 20 engagement with the end of the upper pressure member 11 as shown in Figure 3. The inherent resiliency of said pressure member 11 will thereupon operate to press the powder within the container toward the sifting closure 6. Consequently, as the sliding member 9 of this sifting closure is slid back and forth the powder will be ejected by pressure from 25 said pressure member.

If found more desirable, the pressure member 30 may be constructed with an upper member 11^a and a lower member 12^a similar to those above described with inherent resiliency tending to swing upper member 11^a out of the body portion 1 of the container. The up- 35 standing locking member 13^a provided in this construction is shown as curved inwardly toward the opposite end of the pressure member and the upper pressure member 11^a is shown also curved upwardly at its end so as 40 to frictionally lock with the curved surface of the upstanding member 13^a when the part is engaged. The upstanding curved locking member 13^a is arranged and proportioned so as to be retracted when the closure member 45 6 is swung downwardly similarly to the release described in connection with the corresponding locking member 13 in Figures 2 and 3. Use of the modified construction just described is similar to the use above described 50 and will not be repeated at this time.

I have also shown in Figures 6, 7 and 8 a modified construction of locking member 13^b which is separate from the pressure device, said pressure device providing an upper pressure member 12^b and a lower member 12^a. The locking member 13^b is shown as positively hung as at 15 at the hinge edge of the top closure 6 and adapted to swing over the marginal edge of said pressure member 11^b when 55 said pressure member is forced down to the bottom of the case, as clearly shown in Figure 7. Obviously when the locking member is resting on the top of pressure member 11^b said member is retained in the bottom of the 60 case so that powder may be applied in the 65

body portion. A suitable projecting lip 16 is provided on the locking member 13^b which will be engaged by the shoulder 14 at the hinged end of the closure 6, and force the locking member outwardly off of the pressure member 11^b when the closure is swung down into closed position.

Obviously detail changes and modifications may be made in the construction and use of my improved powder sifter, and I do not wish to be understood as limited to the exact construction except as set forth in the following claims when construed in the light of the prior art.

Having thus described my invention, I 80 claim:—

1. A container having a sifting closure, means for constantly pressing contents of said container toward the sifting closure, and means for holding the said pressure means out of operative position for filling the container.

2. A container having a sifting closure, means for constantly pressing contents of said container toward the sifting closure, means for holding the said pressure means out of operative position for filling the container, and means for automatically releasing said holding means.

3. A container having a sifting closure, and means for pressing contents of the container toward said closure, said means comprising a member having an upper portion and a lower portion the inherent resiliency of which tends to separate said portions and swing the upper portion toward the sifting closure.

4. A container having a sifting closure, means for pressing contents of the container toward said closure, said means comprising a member having an upper portion and a lower portion the inherent resiliency of which tends to separate said portions and swing the upper portion toward the sifting closure, and means for temporarily holding the portions toward each other for filling the container.

5. A container having a sifting closure, means for pressing contents of the container toward said closure, said means comprising a member having upper portion and lower portion the inherent resiliency of which tends to separate said portions and swing the upper portion toward the sifting closure, means for temporarily holding the portions toward each other for filling the container, and means for automatically releasing said holding means when the sifting closure is closed.

6. A container having a sifting closure, means for constantly pressing contents of said container toward the sifting closure, and means for both depressing the pressure means and holding the same depressed out of operative position for filling the container.

7. A container having a sifting closure, means for constantly pressing contents of said container toward the sifting closure, and

means for engaging the pressing means for restraining the same from further expansion when the container is opened for filling.

8. A container comprising in combination with a sifting closure, means for constantly pressing contents of said container toward the sifting closure, said means comprising a one piece leaf spring structure one portion of which bears against the case and another portion of which presses toward the sifting closure by the inherent resiliency of the leaf spring structure.
